Specification of Letters Patent.

Patented Mar. 23, 1920.

Application filed May 28, 1918. Serial No. 237,089.

To all whom it may concern:

Be it known that we, ALBEN E. LUNDELL and ARTHUR B. SPERRY, citizens of the United States, residing at New York, in the county of Bronx, State of New York, and at New York, in the county of New York, State of New York, respectively, have invented certain new and useful Improvements in Telephone-Exchange Systems, of which the following is a full, clear, concise, and exact description.

This invention relates to telephone exchange systems in which automatic switching is employed in extending and completing connections.

More particularly it relates to a telephone system involving a plurality of private branch exchanges, arranged to serve subscribers' lines of both the manual and automatic types, and provided with a novel system of trunk circuits interconnecting the several exchanges in such manner that subscribers belonging to one exchange may readily extend connections to other exchanges, and thence obtain communication with subscribers whose lines terminate therein.

An object of the invention consists generally in the provision of trunk circuits, in a system of this character, by means of which a subscriber at one exchange may extend his line over a trunk to a second exchange, and by the agency of selective switching apparatus extend the connection to a trunk outgoing from the second exchange to a third exchange, and finally by the operation of switching apparatus therein complete the connection to a desired line belonging to such third exchange.

A feature of the present invention consists in the provision of means whereby a connection incoming to a second exchange over an inter exchange trunk circuit from a subscriber's line at a first exchange may be further extended by a selective switch, either to other switches having access to lines individual to said second exchange, or to a second inter exchange trunk outgoing from the second exchange and terminating in a switch at a third exchange.

Another feature relates to means which is incidentally rendered effective, upon two inter exchange trunks being thus connected in tandem at an intermediate exchange, to

automatically convert said trunks into a single through trunk circuit suitable for the transmission of switch operating impulses directly from the calling to the called exchange, without the intervention of any repeating medium at the intermediate exchange.

Still another feature consists in providing a through trunk circuit from a calling to a called exchange, comprising two inter exchange trunks connected in tandem as above described, which remains in a non-talking condition during the switch operating period. Upon the response of the called subscriber means are operated to transform said through trunk circuit from a condition adapted to the transmission of impulses to a condition suitable for the transmission of conversational currents.

A further feature resides in the provision of means whereby an operator at a calling exchange is given supervision of a called line in a distant exchange over said through trunk circuit.

Other and further features will become apparent from a consideration of the following description and the appended claims.

In the drawings, Figures 1, 2, 3 and 4, when arranged consecutively in the order named, disclose so much of a telephone system as is necessary to a comprehensive understanding of the present invention. Fig. 1 shows a portion of a telephone exchange with a manual subscriber's line terminating in an operator's position, and an automatic subscriber's line terminating in automatic switches therein. There is also shown the outgoing end of an inter exchange trunk terminating in a jack at said operator's position, and in multiples of the automatic switches; Fig. 2 shows a portion of the equipment at a second exchange illustrating a selector switch-in which the incoming end of said inter exchange trunk terminates; Fig. 3 shows a second inter exchange trunk outgoing from the second exchange and terminating in a third exchange; Fig. 4 illustrates a connector switch arranged to connect said second trunk to a called line in the third exchange; and Fig. 5 shows the outgoing end of a trunk circuit arranged to extend connections originating in the said second exchange to subscribers' lines belonging to the third exchange.

2
A description will now be given of the operation of the system involving the features of invention.

Assume first that a subscriber provided with a manual substation, as the substation 100, at the first exchange desires to converse with a subscriber whose line terminates at the second exchange, as the line 300, 301. Upon removing his receiver to initiate the call, his line is associated in any well-known manner with an operator's position at the exchange. The operator on learning that the wanted line belongs to another exchange inserts the plug 101 of her cord circuit 102 into the jack 103 of an idle outgoing trunk circuit 104, 105 leading to such exchange. By the insertion of the plug in the jack a circuit is closed from ground, winding of relay 106, sleeve of the plug and sleeve of the jack, winding of relay 107, to battery. Relay 107 energizes and at its right-hand armature closes a circuit to display the supervisory lamp 108. At its left-hand armature, relay 107 applies a ground to the test terminal 109 at a selector switch 110, 111, 112 to render trunk 104, 105 busy to said selector in case a subscriber at an automatic substation, as the substation 113, attempts to extend a call to the second exchange over this trunk circuit. The stepping relay 114 is energized at this time over a circuit from battery, contact 115 of relay 116, left-hand winding of low resistance relay 117, right-hand winding of relay 114, tip of jack 103, tip of plug 101, upper right-hand winding of repeating coil 118 of the operator's cord circuit to ground. At the insertion of the plug 101, a second circuit for relay 114 is also established as follows: battery, winding of called supervisory relay 119, lower right-hand winding of repeating coil 118, ring of plug 101 and ring of jack 103, winding of trunk connecting relay 120, right-hand winding of relay 114, to ground at the repeating coil 118 as above traced. The resistance of this path from battery to ground is so high as compared with the above traced path to ground through relay 114 that the supervisory relay 119 and relay 120 do not receive sufficient current to operate. The stepping relay 114 by attracting its armature closes a bridge across the outgoing end of trunk 104, 105 which results in the energization of the repeating relay 202 at the called exchange, Fig. 2. The circuit of relay 202 may be traced from battery, right-hand winding of such relay, contact 203 of trunk connecting relay 204, trunk conductor 105, outer left-hand armature and contact of relay 116, winding of a polarized relay 121, right-hand winding of relay 117, armature and contact of relay 114, inner left-hand armature and back contact of relay 116, trunk conductor 104, contact 205 of relay 204, left-hand winding of relay 202, upper

right-hand winding of repeating coil 206 to ground. The direction of current in this circuit is such as not to cause the energization of the polarized relay 121. Relay 202 at its front contact closes a circuit for slow relay 207, which in turn prepares a stepping circuit for the operating magnet 208 of the selector switch at the second exchange, and also places a break point in the circuit of the release magnet 210 of such switch. 75

The operator, having obtained the number of the called line 300, 301, of the distant exchange, now presses her calling key 122 and manipulates the sending device 123 to produce a series of short interruptions in the circuit of stepping relay 114 determined by the first digit of such number. In response to these interruptions, relay 114 vibrates its armature, thereby producing a series of interruptions in the above traced circuit of repeating relay 202, which latter relay retracts and attracts its armature correspondingly. At the first retraction of relay 202, an impulse is sent over the following circuit to the primary stepping magnet 208: grounded armature and back contact of relay 202, inner armature and front contact of slow relay 207, left-hand armature and contact of relay 211, conductor 212, winding of slow relay 213, side-switch arm 214 (position 1), winding of magnet 208 to battery. Magnet 208 operates to impart one rotary step to the switch shaft 215. The slow relay 213 also energizes and closes a circuit from ground, over its lower armature, side-switch arm 216 (position 1), to the escape magnet 217. The escape magnet energizes preparatory to releasing the side switch into second position. For each succeeding impulse the magnet 208 gives the shaft 215 a rotary step and finally brings said shaft to rest, at the end of the impulses, with a set of brushes, such as 218, 219, 220 in operative relation to a group of terminals, such as 221, 222, 223, of trunks leading to switches having access to the called line. At the end of this first set of impulses relay 202 holds its armature attracted and after an interval the slow relay 213 deenergizes to open the escape magnet circuit. Said escape magnet now deenergizes and passes the side switch into position 2. 100

When the side switch reaches position 2, the escape magnet 217 is again energized over a circuit from battery, winding of such magnet, left-hand armature and contact of magnet 210, side-switch arm 216 (position 2), conductor 224, contact 225, now closed, side-switch arm 226 (position 2), to ground. A circuit for the secondary stepping magnet 125 209 is now closed from ground, side-switch arm 227 (position 2), contact and armature of magnet 217, contact and armature and winding of magnet 209 to battery. Magnet 209 thereupon energizes and advances shaft 130

215 one vertical step to place brushes 218, 219, 220 in contact with the first set of terminals in the selected group, and at the same time interrupts its own circuit. At the end 5 of this first vertical step contact 225 is opened to disrupt the above traced circuit of escape magnet 210. If, however, the first trunk in the group, upon which the brushes 218, 219, 220 are now standing, is busy, the 10 test terminal 223 thereof will be grounded over an arm similar to arm 228 at some other selector switch. Escape magnet 217 is therefore held energized over the following path, battery, winding of such magnet, contact 15 and left-hand armature of magnet 210, side-switch arm 216 (position 2), conductor 224, test brush 220, to a grounded terminal such as 223. Magnet 209 continues to operate until the brushes 218, 219, 220 reach an idle 20 trunk, at which time the escape magnet 217 deenergizes to escape the side switch into third position.

The selector switch at the second exchange, Fig. 2, is now standing with a set of 25 its brushes 218, 219, 220 in contact with the terminals of a trunk leading to a connector switch, indicated by the brushes 409', 410' and 411', having access to the called line 300, 301 in said second exchange. The connector 30 35 409', 410', 411' is in every respect similar to the connector shown in full at the third exchange, Fig. 4, and from this point on the description of the completion of the call from the subscriber's line 100 to subscriber's line 300, 301 will be given with reference to the connector circuits shown in Fig. 4.

As the side-switch arm 228 of the selector goes to third position the following circuit 40 is established for a relay similar to relay 400, Fig. 4, of the connector illustrated by brushes 409', 410', 411', at the second exchange: ground, arm 228 (position 3), brush 220, terminal 223, a test conductor similar to conductor 401, Fig. 4, right-hand armature 45 and back contact of release magnet 402, side-switch arm 403 (position 1), winding of relay 400, to battery. Relay 400 energizes and prepares an impulse circuit for the connector operating magnets 404 and 405, and 50 at its left-hand armature said relay 400 also interposes a break point in the circuit of release magnet 402. The apparatus is now in condition to receive the second or tens series 55 of impulses. The operator accordingly operates her sender 123 to produce the desired number of interruptions in the circuit of stepping relay 114 at the calling exchange. For each such interruption the repeating relay 202 retracts and attracts its armature, 60 and at the first retraction thereof a circuit is closed for the primary stepping magnet 404 of the connector switch. This circuit is traceable from the grounded armature and back contact of relay 202, inner armature 65 and contact of relay 207, left-hand armature

and contact of relay 211, conductor 212, winding of slow relay 213, side-switch arm 214 (position 3), brush 218, terminal 221, a trunk conductor similar to conductor 406, conductor 407, outer right-hand armature 70 and contact of relay 400, side-switch arm 408 (position 1), winding of magnet 404, to battery. Magnet 404 energizes and advances the connector brushes 409', 410' and 411' one rotary step. At the same time the 75 slow relay 213 energizes to close a circuit as follows for the connector escape magnet 412: ground, upper armature and front contact of relay 213, side-switch arm 232 (position 3), brush 219, terminal 222, conductors 413 80 and 414, side-switch arm 415 (position 1), armature and contact of relay 416; winding of escape magnet 412, to battery. Said escape magnet energizes preparatory to advancing the connector side switch into second position. For each succeeding vibration of the repeating relay 202 the connector primary magnet 404 operates to impart a rotary step to the brushes 409', 410' and 411'. At the termination of this set of 85 impulses said brushes are brought to rest in operative relation to a group of terminals containing the terminals 428', 429', 430' of the called subscriber's line 300, 301. Relay 202 now remains energized and after a sufficient 90 interval the slow relay 213 releases to interrupt the circuit traced for escape magnet 412. Said escape magnet thereby deenergizes to pass the side switch into its second position. Side-switch arm 403 engages 100 its second contact before breaking connection with its first contact, and therefore the relay 400 remains energized over its inner right-hand armature and contact, second position contact of arm 403, to the grounded 105 test wire 401.

The operator now sends out the final or units series of impulses, causing as before, the vibration of the repeating relay 202. In response to the first retraction of relay 202 110 an impulse is sent to the connector secondary magnet 405. The circuit for this magnet leads from the grounded armature of relay 202, over the previously traced path to side-switch arm 408, now in position 2, and thence to magnet 405 and battery. Relay 213 again energizes and completes a circuit for escape magnet 412, which leads as before described from ground, upper armature of relay 213, to conductor 414, and 115 from here by way of side-switch arm 415 (position 2), to escape magnet 412 and battery. Magnet 412 energizes to subsequently escape the side switch to third position. A parallel circuit to the one just traced for 120 magnet 412 is also completed to energize the slow relay 419. At each impulse sent to magnet 405 such magnet operates to move the brushes 409', 410', 411' over the terminals of the selected group and finally brings 125 130

them to rest in contact with terminals 428', 429', 430' of the called line 300, 301. At the end of the units impulses magnet 412 de-energizes as before to advance the connector 5 side switch into third position.

Assume first that, when the brushes 409', 410' and 411' arrive on the terminals of the called line, such line is already engaged. In this case a non-selectable potential will be 10 found on the test terminal 430', full potential having been removed or reduced in any well-known way in the event the line is busy as a calling line, or having been reduced by a circuit leading to ground at the left-hand 15 armature and contact of a test relay 417 with side-switch arm 418 in third position, or to ground through the right-hand low resistance winding of relay 417 with side-switch arm 418 in position 4 at some other final 20 selector if the line is busy as a called line. In either case the test relay 417 of the switch shown does not receive sufficient current through its high resistance winding to energize. With the side-switch magnet now 25 standing in position 3, the energizing circuits of relays 400 and 419 are opened. As soon thereafter as relay 419 releases its right-hand armature the relay 400 becomes inert, thereby closing a circuit from battery, 30 winding of release magnet 402, left-hand armature and contact of relay 400, primary off-normal contact 420, to ground. Release magnet 402 attracts its armatures and releases the brushes 409', 410', 411', and the 35 side switch to normal position. As the switch reaches its normal position, primary off-normal contact 420 is opened, which however, does not occur until slightly after the closure of the normal contact 421. Hence 40 the magnet 402 remains energized over the following circuit: battery, winding of magnet 402, left-hand armature of relay 400, normal contact 421, resistance 422, front contact and right-hand armature of magnet 45 402, to the grounded third wire 401. When the connector side switch reaches its first position a path is closed from the secondary winding of busy tone transformer 423, contact and left-hand armature of magnet 402, 50 side-switch arm 424 (position 1), condenser 425, side-switch arm 426 (position 1), to the trunk conductor 413 leading back to the first selector. In any well-known manner this busy tone is inductively transmitted back to 55 the operator's telephone set. Being thus informed of the busy condition of the called line, the operator notifies the calling subscriber of such fact, and removes the plug 101 from jack 103. The relay 114 thereupon 60 de-energizes and opens the bridge across trunk conductors 104, 105, causing the repeating relay 202 to become inert. The slow relay 207 now de-energizes and closes the 65 following circuit for the first selector release magnet 210: battery, winding of magnet

210, conductor 233, back contact and outer armature of relay 207, conductor 234, inner left-hand armature and back contact of relay 235, primary off-normal contact 236, to ground. Magnet 210 thereupon operates to 70 restore the selector and its associated side switch to normal. When brush 220 moves off the terminal 223, ground is removed from wire 401 and the release magnet 402 retracts its armatures. At the calling exchange the 75 removal of plug 101 also severed the circuit of relay 107, which retracted its armatures to efface the lamp 108, and to remove the busy condition from terminal 109. All apparatus is now in its normal restored position. 80

If, however, the called line 300, 301 is idle at the time connection is extended thereto, full potential is present upon the test terminal 430'; when the final selector side switch passes to third position the test relay 417 is, therefore, energized over a circuit including its high resistance winding. Relay 417 at its right-hand armature closes a circuit as follows: battery, winding of escape magnet 412, contact and armature of 90 relay 415, side-switch arms 415 and 427 (position 3), right-hand armature and low resistance winding of relay 417 to ground. Relay 417 at its left-hand armature shunts out the high resistance winding, thus reducing the potential of test multiples 430' to 95 make the called line non-selectable to other switches. A parallel circuit to the one just traced for magnet 412 is also completed for the slow relay 419 as side-switch arm 427 goes to third position. Relay 400 at this 100 time remains energized to hold the release circuit open over a circuit from battery, winding of such relay 400; its inner right-hand armature and contact, contact and 105 right-hand armature of the slow relay 419, to the grounded third conductor 401. The escape magnet 412 energizing in the above traced circuit applies ringing current to the called line as follows: ringing source 431, 110 relay 416, inner armature and contact of magnet 412, side-switch arm 432, brush 410', terminal 429', over the loop of line 301, 300, terminal 428', brush 409', side-switch arm 423, to ground at the outer armature of 115 magnet 412. When the called party responds the relay 416 operates, being marginal, and opens the circuit of magnet 412, which de-energizes and passes the side switch into position 4. In this position the relay 120 400 is maintained energized by a circuit leading over arm 403 to the grounded conductor 401. As side-switch arm 427 leaves position 3, the circuit for relay 419 is broken, but being slow to release, said relay holds 125 its armatures for an interval subsequent to the arrival of arm 426 in fourth position. This causes an impulse to be reverted to the first selector over the following circuit: grounded left-hand armature and contact of 130

relay 419, side-switch arm 426 (position 4), conductor 413, terminal 222, brush 219, side-switch arm 232 (position 3), upper armature and back contact of relay 213, inner 5 lower armature and back contact of relay 238, lower right-hand winding of repeating coil 206, winding of relay 237, to battery. Relay 237 closes the following circuit for the first selector escape magnet 217: ground- 10 ed armature and contact of relay 237, lower middle armature and contact of relay 238, inner left-hand armature and back contact of relay 239, side-switch arm 216 (position 3), winding of magnet 217, to battery. The 15 escape magnet energizes, and as soon thereafter as the slow relay 419 retracts its armatures to open the momentarily closed circuit of relay 237, said escape magnet again deenergizes to release the side switch to position 4. Upon the side-switch arms 232 20 and 239 reaching position 4, a circuit is closed for relay 237, traceable from battery, winding of said relay, lower right-hand winding of repeating coil 206, inner lower 25 armature and back contact of relay 238, upper armature and back contact of relay 213, side-switch arm 232 (position 4), brush 219, terminal 222, conductor 413, side-switch arm 432 (position 4), brush 410', terminal 429', 30 over the loop of station 301, 300, terminal 428', brush 409', side-switch arm 433, conductor 406, terminal 221, brush 218, side-switch arm 239 (position 4) upper right-hand winding of coil 206 to ground.

35 The relay 237 thus energizes in series with the called line, and operates to close a circuit for the trunk connecting relay 204 at the incoming end of the inter office trunk circuit 104, 105. Such circuit leads from 40 grounded armature and contact of relay 237, conductor 240, left-hand winding of relay 211, winding of relay 204, to battery. Relay 204 by attracting its armatures serves to remove the connection of trunk conductors 104, 105 with the windings of repeating relay 202 and to connect said conductors directly to the left-hand portion of repeating coil 206. The source of current fed to conductors 104, 105 from the repeating coil 50 206 now flows in the proper direction for energizing polarized relay 121. Relay 121 according attracts its armature and closes a circuit from battery, armature and front contact of relay 121, windings of relays 116 and 124 to ground at the right-hand armature of relay 107. Relays 116 and 124 energize and lock up over a circuit extending from battery, contact 115, right-hand armature of relay 116, windings of relays 116 55 and 124 to ground at the right-hand armature of relay 107. By the attraction of both the armature of relay 121 and the right-hand armature of relay 116, the previously traced low resistance path from battery through the windings of relays 117 and 114 60 to ground at the upper right-hand winding of repeating coil 118 is now opened. This causes an increased flow of current through the supervisory relay 119 and trunk connecting relay 120 in the circuit hereinbefore 70 described. Relay 119 energizes and closes a circuit for the called supervisory lamp 125, which is displayed to inform the operator that the called party has responded. Relay 120 by attracting its armatures electrically 75 connects the trunk 104, 105 to the operator's cord circuit. When relay 202 was disconnected from conductors 104 and 105 by the relay 204, the circuit for relay 207 was at the same time opened. This relay being 80 slow, however, does not deenergize until relay 241 has time to operate to close a holding circuit therefor. Premature release of the switches is thus prevented. The connection is now complete for conversation. 85

After conversation is finished, the called subscriber by replacing his receiver opens the above traced circuit for relay 237. This relay in turn causes the deenergization of trunk connecting relay 204, which disconnects the trunk 104, 105 from repeating coil 205, and again connects said trunk in series with the repeating relay 202. This results in a reversal of battery current through polarized relay 121. Consequently relay 90 121 becomes inert and closes at its armature and back contact a low resistance path from battery to ground as above traced in parallel with the circuit over which called supervisory relay 119 is at this time being energized. This short circuit around relays 95 120 and 119 causes a sufficient reduction in current to permit their deenergization, the former opening the outgoing end of the trunk 104, 105 and the latter relay serving 100 to extinguish the lamp 125. The operator, thus being informed that conversation is finished, removes her plug 101 from the trunk jack 103. Restoration of the switching mechanism thereupon takes place as 105 already described.

It will now be assumed that a subscriber at an automatic substation, as substation 113 belonging to the first exchange desires to be connected with the line 300, 301. Upon 115 the removal of the receiver at substation 113, the calling line is connected in a well-known manner, as by means of a line switch, to a trunk leading to an idle selector switch whose brushes are shown at 110, 111 and 120 112. The subscriber now operates his dial 126 to position the selector brushes 110, of trunks, such as terminals 127, 128 and 109 of trunks 104, 105, leading to the distant 125 exchange to which the called line belongs. The selector then proceeds to automatically test the terminals 109 and in the well-known manner brings its brushes 110, 111, 112 to rest in connection with the first idle 130 trunk found. The following circuit is now

closed for stepping relay 114: battery, contact 115 of relay 116, left-hand winding of low resistance relay 117, right-hand winding of relay 114, contact 124, terminal 127, 5 brush 110, over the route substation 113, brush 111, terminal 128, winding of relay 130, contact 131, left-hand winding of relay 114, to ground. Relay 130 closes an energizing circuit for the supervisory relay 107, which completes a circuit for lamp 108. The operator is thereby informed that the trunk 104, 105 is engaged and will not attempt to make connections with the same by means of her cord circuits. The stepping relay 114 attracts its armatures and closes a bridge, including polarized relay 121, across the trunk conductors 104 and 105 to energize the repeating relay 202 at the called exchange. This circuit is precisely 15 the same as that traced in connection with an operator's call, the direction of current flow being such as not to affect the polarized relay 121.

By manipulating his dial 126, the subscriber at substation 113 causes the stepping relay 114 to vibrate its armature in a manner similar to that already described in connection with the operation of the operator's calling device 123. At each such interruption of the calling line, the relay 130 retracts its armature, but relay 107 being slow on release does not have time to de-energize to efface lamp 108. From this point on the operation of stepping relay 114 under the control of the calling subscriber serves to bring about the operation of the first and final selectors at the called exchange. As has been described, when the called party responds and the trunk connecting relay 204 is operated to telephonically connect the incoming end of trunk 104, 105 to the called line, a current reversal results as before, and polarized relay 121 now becomes energized. Relay 121 completes the circuit at its armature from battery through windings of relay 116 and the trunk connecting relay 124 to ground at the right-hand armature and front contact of relay 107. Relay 116 is locked up as before 30 described and connects the outgoing end of the trunk circuit 104, 105 to the calling line. A complete through telephonic connection is now established from the calling line in the first exchange to the called line in the second exchange and conversation may take place.

It has thus been described how a subscriber belonging to one exchange may obtain connection with a subscriber at another exchange over an inter exchange trunk. In this case the inter exchange trunk performs the functions of a terminating trunk at the called exchange, serving to extend the calling line to automatic switches therein, which 45 switches are then operated to complete the

connection to the desired line. It will now be explained in what manner the above mentioned trunk may be joined in tandem to a second inter exchange trunk outgoing from the second exchange and leading to a third 70 exchange. For this purpose it will be assumed that the subscriber at substation 100 of the first exchange desires to converse with the subscriber at substation 434 at the third exchange, Fig. 4. On the initiation of the 75 call the line of substation 100 is extended to the operator's position and the operator connects said line to an outgoing trunk circuit 104, 105 leading to the second exchange. The completion of operating circuits for relays 107 and 114 at the calling exchange and for relay 202 at the second exchange being identical with that hereinbefore described, need not be repeated. The operator, having 80 been informed by the calling subscriber that connection is wanted with a line at the exchange shown in Fig. 4, actuates her sender 123 in accordance with the first digit of the called number. In the same manner as hereinbefore described, the repeating relay 202 85 at the second exchange, Fig. 2, vibrates its armature in response to the sender 123 and transmits a corresponding number of impulses to the primary magnet 208 of the selector switch. The magnet 208 thereby 90 operates to rotate the shaft 215 and finally brings the same to rest with a set of brushes 218, 219, 220 in operative relation to a group of terminals such as terminals 242, 243, 244 95 of trunks outgoing from the second exchange and leading to the third exchange. In this instance the group brush 245, carried 100 by shaft 215, has been rotated so that at the end of the group selecting movement it stands on the contact 246. As soon now as relay 213 and escape magnet 217 deenergizes 105 to pass the side switch into second position, a circuit is established as follows: ground, side-switch arm 228 (position 2), group brush 245, contact 246, winding of relay 239, 110 to battery. Relay 239 energizes and closes a new circuit for itself from battery, winding of relay 239, right-hand armature and contact of such relay, buck contact and right-hand armature of relay 211, conductor 234, 115 outer armature and front contact of relay 207, to ground, said relay 207 being operated at this time. The escape magnet 217 again operates as above described and closes the stepping circuit for the secondary magnet 120 209, which operates to drive the brushes 218, 219, 220 over the terminals of the selected group of outgoing trunks. When test brush 220 encounters a terminal 244 of an idle 125 trunk, the escape magnet 217 deenergizes and advances the side switch into third position. As the arm 227 reaches third position the following circuit is completed from the trunk controlling relays 238 and 247: 130 battery, windings of relays 247 and 238,

outer left-hand armature and front contact of relay 239, side-switch arm 227, to ground. These relays operate to remove the repeating coil 206 from the incoming trunk circuit and at the same time lock up as follows independently of side-switch arm 227: battery, windings of relays 247 and 238, lowermost armature and contact of relay 238, conductor 234, to ground at the outer armature and front contact of relay 207. In position 3 of the side switch the escape magnet 217 is again energized over a circuit from battery, winding of such magnet, contact and left-hand armature of magnet 210, side-switch arm 216 (position 3), inner left-hand armature and front contact of relay 239, to ground. When trunk relay 247 is energized, it establishes a circuit as follows for the trunk closing relay 204: lowermost ground-ed armature of relay 247, conductor 240, left-hand winding of relay 211, winding of relay 204, to battery. Relay 204 operates to disconnect repeating relay 202 and to close the incoming end of trunk 104, 105. Relay 211 also operates in series with relay 204, thereby opening the previously traced locking circuit of relay 239. This relay 239 now de-energizes to disrupt the above described circuit of escape magnet 217, which magnet 30 thereupon passes the side switch into its fourth position.

It will be noted that the circuit of relay 207 is opened when repeating relay 202 is disconnected from the trunk conductors 104, 105. The relay 207 being slow, however, does not release before the selector side switch has reached fourth position, at which time a circuit is completed to energize the relay 241 to thereby close a new circuit to hold said relay 207 energized. This circuit may be traced from battery, at the called exchange, Fig. 3, right-hand winding of repeating relay 305, contact 306, over the conductor 307 of the trunk interconnecting the second and third exchanges, contact 308 of relay 313, conductor 309, terminal 242, brush 218, side-switch arm 239 (position 4), upper armature and front contact of relay 238, upper armature and front contact of relay 247, upper armature and contact 203 of relay 204, trunk conductor 105, outer left-hand armature and contact of relay 116, winding of polarized relay 121, right-hand winding of low resistance relay 117, armature and contact of relay 114, inner left-hand armature and back contact of relay 116, trunk conductor 104, contact 205 and lower armature of relay 204, winding of relay 241, inner lower armatures and front contacts of relays 247 and 238, upper armature and back contact of relay 213, side-switch arm 232 (position 4), brush 219, terminal 243, conductor 310, winding of relay 311, contact 312 of relay 313, winding of polarized relay 314, trunk conductor 315, contact 316 of relay 317, left-hand winding of relay 305, upper right-hand winding of repeating coil 318, to ground. By this operation the stepping relay 202 at the second exchange is disconnected from the trunk circuit, and current 70 is now delivered from the repeating relay 305 at the called exchange over the two conductors of the trunk in series back through the second exchange to the first or calling 75 exchange. It will be observed that the direction of current flow through polarized relay 121 is still the same; and consequently this relay remains inert. Also the direction of flow through the polarized relay 314 so at the intermediate exchange is such as not to operate the same at this time. Relay 305 by energizing in the above traced circuit closes at its armature and front contact a 80 circuit for the slow relay 319. The apparatus is now in condition to receive the next 85 series of impulses.

For the purpose of this description, the called exchange, illustrated by the right-hand portion of Fig. 3 and by Fig. 4, is 90 assumed to be of such capacity as to warrant only the use of final or connector switches. Hence the incoming end of the trunk circuit at the called exchange leads directly to a connector switch, such as that 95 shown in Fig. 4. The next manipulation of the operator's sender 123 serves, therefore, to control the stepping relay 114 in accordance with the tens digit of the called 100 number. The relay 114 by vibrating its armature operates to intermittently open and close the above described circuit for repeating relay 305 at the called exchange. When slow relay 319 is energized, it closes the following circuit for relay 400 at the 105 connector: grounded left-hand armature, and contact of relay 319, conductor 401, right-hand armature and back contact of magnet 402, side-switch arm 403 (position 1), winding of relay 400, to battery. Upon 110 the first retraction of repeating relay 305, a circuit is now closed as follows for the primary magnet 404: grounded armature and back contact of relay 305, right-hand armature and contact of relay 319, winding 115 of slow relay 320, back contact and upper armature of relay 321, conductors 406 and 407, outer right-hand armature and contact of relay 400, side-switch arm 408 (position 1), winding of magnet 404, to battery. At 120 the same time relay 320 energizes and places a ground upon the conductor 413, which results in the energization of the connector escape magnet 412 in a manner already described. The primary magnet 404 operates 125 in response to the tens impulses to rotate the connector brushes 409, 410 and 411 into operative relation to the group of line terminals containing the terminals 428, 429 and 430 of the desired subscriber's line 434. 130

The operator now actuates the sender 123 to produce the final operation of the stepping relay 305 in accordance with the units digit. At each retraction of relay 305 an impulse is sent to the connector secondary magnet 405 over the above traced circuit to the arm 408, now in second position, and thence to said magnet 405. The side switch went to second position subsequent to the transmission of the tens series as was clearly explained hereinbefore. The secondary magnet 405 thus operates to advance brushes 409, 410 and 411 over the selected group and into engagement with terminals 428, 429 and 430 of the called line. If such line is busy, release magnet 402 is operated to restore the connector, and the busy tone is applied to conductor 413 as above explained. The operator hearing this busy tone informs the calling subscriber that the desired line is busy, and removes plug 101 from trunk jack 103. Removal of plug caused the de-energization of relays 107 and 114. Relay 114, by retracting, opens the bridge across trunk conductors 104, 105, which in turn results in the de-energization of relays 305 and 241. Relay 241, by releasing, causes the slow relay 207 to de-energize. A circuit for the selector release magnet 210 is now closed from battery, winding of such magnet, conductor 233, back contact and outer armature of relay 207, conductor 234, inner left-hand armature and back contact of relay 235, primary off-normal contact 236 to ground. Release magnet 210 thereupon operates to restore the selector and its associated side switch to normal. As soon as the selector and its associated side switch reach their normal positions, ground is removed from conductor 234, and trunk relays 247 and 238 de-energize. Relay 247, by retracting its armatures, opens the circuit of relays 211 and 204, which in turn permit their armatures to drop back. All apparatus is now in its normal restored condition.

If, however, the called line 434 is idle when the connector arrives upon its terminals 428, 429, 430, test relay 417 operates, relay 419 remains energized, and escape magnet 412 again energizes to apply ringing current, all as was clearly explained hereinbefore. When the subscriber at substation responds, ringing cutoff relay 416 operates and the escape magnet 412 advances the side switch to position 4. During the period the slow relay 419 is retaining its armatures after thus having its circuit opened, and after the side switch has reached fourth position, a momentary circuit is established as follows: ground, left-hand armature and contact of slow relay 419, side-switch arm 426 (position 4), conductor 413, armature and back contact of relay 330, lower right-hand winding of repeating coil 318, wind-

ing of relay 322, to battery. Relay 322 closes a circuit from battery, winding of trunk relay 317, upper winding of trunk relay 321 to ground at the armature of relay 322. Relay 321 operates and establishes the following circuit to hold relay 322 energized in series with the called line after the slow relay 419 at the connector deenergizes: battery, winding of relay 322, lower right-hand winding of repeating coil 318, 75 back contact and armature of relay 320, conductor 413, arm 432 (position 4), brush 410, terminal 429, over the loop of substation 434, terminal 428, brush 409, arm 433, conductor 406, upper armature and front contact of relay 321, upper right-hand winding of repeating coil 318, to ground. Relay 317 operates to connect repeating coil 318 to the incoming trunk circuit and also disconnects repeating relay 305 at contacts 306, 80 316. Battery current is now fed from repeating coil 318 back over the trunk circuit to the calling exchange in the opposite direction to that supplied by relays 202 and 305 during the switch operating period. 90 Polarized relay 121 now responds to such reversal of current and in the same manner as hereinbefore described, causes the display of lamp 125, and the operation of the trunk closing relay 120. Polarized relay 314 at the 95 outgoing end of the trunk in the intermediate exchange likewise responds to this current reversal to close the following circuit: battery, windings of trunk relays 323 and 313, contact and armature of relay 314, to 100 ground. Relays 323 and 313 operate to connect repeating coil 324 in the trunk circuit. It will be observed the battery at the left-hand portion of repeating coil has now been substituted by battery at the repeating coil 105 318, to supply talking current to the calling exchange. The direction of current is maintained the same, however, so that relay 121 remains actuated. A complete talking connection has thus been established from a 110 calling exchange, through an intermediate and to a called exchange.

When the called party hangs up his receiver at the end of conversation, relay 322 de-energizes and releases relays 317 and 321. 115 Relay 317 on falling back causes a reversal of current through polarized relay 314, which in turn becomes inert and causes relays 323 and 313 to retract. Release of the relay 323 reverses current through polarized 120 relay 121, which retracts to cause the de-energization of relays 119 and 120. Called supervisory lamp 125 is therefore effaced to inform the operator that conversation is completed. The operator removes the plug 125 101 which effects a restoration of the switching apparatus.

It is thought that the manner in which an automatic line at the first exchange may be extended into connection with a called line 130

at the third exchange, is obvious from the foregoing description. It is therefore unnecessary to trace out such a call in detail.

Considering Fig. 5 there is shown a portion of the outgoing end of a trunk circuit arranged to extend calls originating in the second exchange to the third exchange. A subscriber at an automatic substation (not shown) in the second exchange, Fig. 2, upon initiating a call to the third exchange, Fig. 4, connects his line by means of line and selector switches (not shown) to the trunk conductors 500, 501. A circuit is thereupon established from battery, armature and back contact of polarized relay 502, left-hand winding of relay 503, right-hand winding of stepping relay 504, contact 505, conductor 500, back over the loop of the calling line (not shown) and thence returning by way of conductor 501, winding of relay 506, contact 507, to the left-hand winding of relay 504 and ground. From here on the operation of the circuits shown in Fig. 5 is substantially identical to that given in connection with the establishment of a call from the automatic substation 113, Fig. 1, to a wanted line in a distant exchange.

In the disclosure of the present invention, the originating exchange only is shown as being arranged to accommodate both manual and automatic lines, and the third or called exchange is described as a satellite of the intermediate exchange. Yet it is to be understood that the invention is not limited to this specific arrangement. In fact each exchange may be provided with both classes of lines, and also with inter exchange trunk circuits such that a calling line, whether manual or automatic, at any exchange in the system may be afforded the above described trunking facilities with any other exchange in the system.

What is claimed is:

1. In a telephone system, a plurality of exchanges, a trunk circuit outgoing from a first and terminating in a switch at a second of said exchanges, a source of talking current in said trunk circuit, a line terminating at the second exchange, a second trunk circuit outgoing from the second exchange and terminating in a switch at a third of said exchanges, means for sending impulses over the trunk from the first to the second exchange, said switch at the second exchange being responsive thereto to connect said first trunk either to said line or to said second trunk, and means operated by the establishment of such latter connection to disable said source of current and to convert said trunks into a single through trunk arranged to transmit impulses directly from the first to the third exchange, said switch at the third exchange being responsive to such impulses to further extend said through trunk circuit.

2. In a telephone system, a plurality of exchanges, a trunk circuit outgoing from a first and terminating in a switch at a second of said exchanges, a line terminating in the second exchange, a source of talking current in said trunk circuit for supplying said line, a second trunk circuit outgoing from the second and terminating in a switch at a third exchange, means for sending impulses over the two conductors of the trunk in series from the first to the second exchange, said switch at the second exchange being responsive thereto to connect said first trunk either to said line or to said second trunk, and means operated by the switch in the establishment of such latter connection to disable said source of current and to convert said trunks into a single through trunk arranged to transmit impulses directly from the first to the third exchange over its two conductors in series, said switch at the third exchange being responsive to such impulses to further extend said through trunk.

3. In a telephone system, a plurality of exchanges, a trunk circuit outgoing from a first and terminating at a second of said exchanges, a line terminating in the second exchange, a battery in said trunk circuit for supplying said line, a second trunk circuit outgoing from the second and terminating in a third exchange, means for sending impulses over the trunk from the first to the second exchange, means responsive thereto to connect said first trunk either to said line or to said second trunk, means operated by the establishment of such latter connection to disconnect said battery and to convert said trunks into a single through trunk circuit arranged to transmit impulses directly from the first to said third exchange, a called line, means at the third exchange responsive to such impulses for extending said through trunk circuit to the called line, a plurality of sources of talking current associated with said through trunk circuit but disconnected therefrom during the transmission of impulses, and means operated upon the response of the called subscriber for rendering said sources of current effective.

4. In a telephone system, a plurality of exchanges, a connecting circuit outgoing from a first and terminating at a second of said exchanges, a line terminating in the second exchange, a battery in said connecting circuit for supplying said line, a second connecting circuit outgoing from the second and terminating at a third exchange, means for sending impulses over the connecting circuit from the first to the second exchange, means responsive thereto to connect said first connecting circuit either to said line or to said second connecting circuit, means operated by the establishment of such latter connection to disconnect said battery and to convert said connecting circuits into a single

through trunk circuit arranged to transmit impulses directly from the first to the third exchange, a called line, means at the third exchange responsive to such impulses for extending said trunk circuit to the called line, a plurality of sources of talking current associated with said trunk circuit but disconnected therefrom during the transmission of impulses, means operated upon the response 10 of the called subscriber for rendering one of said sources effective, means operated for thereupon reversing the current in said trunk circuit, and means responsive to such current reversal for rendering the other of 15 said sources effective.

5. In a telephone system, a plurality of exchanges, a connecting circuit outgoing from a first and terminating at a second of said exchanges, a second connecting circuit 20 outgoing from the second and terminating in a third exchange, means for sending impulses over said first connecting circuit to the second exchange, means responsive thereto for connecting said first circuit to 25 said second circuit, means operated by the establishment of such connection for converting said connecting circuits into a single through trunk circuit adapted to transmit impulses directly from the first to the third 30 exchange, a called line, means at the third exchange responsive to such impulses for extending said trunk to said line, a source of talking current at said first and third exchanges associated with said trunk circuit 35 but ineffective during the transmission of impulses, means operated upon the response of the called subscriber for rendering effective said source at the third exchange, means also operated to reverse the current 40 over said trunk circuit and means responsive to such current reversal for rendering effective said source of talking current at the first exchange.

6. In a telephone system, a plurality of exchanges, a connecting circuit outgoing from a first and terminating at a second of said exchanges, a second connecting circuit outgoing from the second and terminating at a third exchange, means for sending impulses 45 over the connecting circuit from the first to the second exchange, means responsive thereto for connecting said first circuit to said second circuit, means operated by the establishment of such connection for 50 converting said circuits in a single trunk circuit adapted to transmit impulses directly from the first to the third exchange, a called line, means at the third exchange responsive to such impulses to extend said trunk circuit 55 to the called line, a plurality of sources of talking current associated with said trunk circuit ineffective during the transmission of impulses, means operated upon the response of the called subscriber for rendering one of 60 said sources effective, such source serving

to thereupon reverse the current over said trunk circuit, and polarized relays operated in response to such reversal of current to render effective the remaining of said sources of talking current.

7. In a telephone system, a calling line, a trunk circuit terminating in a switch, means for associating said line with said trunk, a second trunk circuit terminating in a switch, a called line, means associated with the calling line for sending impulses over said first trunk, said first switch being responsive thereto to connect said first trunk to said second trunk, means operated upon the establishment of such connection for converting said trunks into a single circuit arranged to transmit impulses directly from said sending means to said second switch, said second switch being responsive thereto to extend the connection to the called line, a source of talking current for each of said trunks, means operated upon the response of the called subscriber for connecting one of said sources to said second trunk, means for thereupon reversing the current over said first trunk, and means responsive to such current reversal for connecting the other source of current to said first trunk for conversation.

8. In a telephone system, a connecting circuit terminating in a switch, a second connecting circuit terminating in a second switch, an impulse device for sending impulses over the circuit leading to said first switch, said first switch being responsive to said impulses to connect said first circuit to said second circuit, means operated by the establishment of such connection to convert said circuits into a single trunk circuit adapted to transmit impulses directly from said impulse device to said second switch, a called line, said second switch being responsive to such impulses to extend said trunk circuit to the called line, a plurality of sources of talking current associated with said trunk circuit but ineffective during the transmission of impulses, means operated upon the response of the called subscriber for rendering effective one of said sources of current, such source serving to thereupon reverse the current over said trunk circuit, and means responsive to such reversal of current for rendering effective the remaining of said sources of talking current.

9. In a telephone system, an established connection from a calling line to a called line comprising a trunk circuit extending from a first exchange through a second to a third exchange, said trunk circuit being arranged to transmit impulses directly from the first to the third exchange during the establishment of said connection, sources of talking current associated with said trunk circuit but disconnected therefrom during the transmission of impulses, means oper-

ated upon the response of the called subscriber for connecting one of said sources to said trunk, such source serving to reverse the flow of current over said trunk, and means responsive to such reversal of current for connecting the other of said sources of current to said trunk circuit for conversation.

10. In a telephone system, a plurality of exchanges, an operator's position in a first of said exchanges, a supervisory signal at said position, a connecting circuit outgoing from said first and terminating at a second exchange, a second connecting circuit outgoing from the second and terminating in a third exchange, means for sending impulses from the first to the second exchange, means responsive thereto for connecting said first circuit to said second circuit, means operated by the establishment of such connection for

converting said circuits into a single trunk circuit arranged to transmit impulses directly from the first to the third exchange, a called line, means at the third exchange responsive to such impulses to extend said trunk circuit to the called line, a source of talking current associated with said trunk circuit normally disconnected therefrom during the transmission of impulses, means operated upon the response of the called subscriber for rendering said source of current effective, such source serving to thereupon reverse the current over said trunk circuit, and means responsive to such reversal of current for operating said supervisory signal.

In witness whereof, we have hereunto subscribed our names.

ALBEN E. LUNDELL.
ARTHUR B. SPERRY.
